EDGE TRIMMING ATTACHMENT

Joseph Chudner, Brooklyn, N. Y.

Application January 23, 1934, Serial No. 707,993

3 Claims. (Cl. 112—122)

This invention relates to a device or attachment which may be used advantageously in conjunction with a sewing machine so that goods can be stitched and edge trimmed in one operation.

Some of the advantages of the device or attachment are: it enables convenient adjustments to suit varieties of work and to compensate for wear of parts thereof; it prevents material from interfering with the proper operation of the 5 needle, by turning the trimmed portion sidewise and, at the same time, allows an operator to clearly view the work while operating the machine to secure accurate work with clean cut edges; and it embodies novel features of construction and operation whereby sewing machines already in use 10 may be equipped with cutters without requiring alteration of the machines.

The invention consists in the improvements as hereinafter described and claimed and as illustrated by way of example in the accompanying drawings, in which

Figure 1 is a plan view of the device or attachment operatively connected with portions of a sewing machine;

Fig. 2 is a view looking at the under side of the cutter unit;

Fig. 3 is a section taken on the line 3—3 of Fig. 1;

Fig. 4 is a section taken on the line 4—4 of Fig. 1, a portion of the link being broken away;

Fig. 5 is an end view of the connection applied to the feed lifting rock.

The device or attachment, by way of example, is shown applied to a sewing machine, and in the drawings there are illustrated portions of the machine directly involved consisting of a bed 10, a feed lifting rock 11, supported by suitable bearings on the under side of the bed 10 near the rear, and a throat, feed and needle plate 12, which is detachably secured to the bed 10 by screws 13, the plate 12 being flush with the upper surface of the bed 10.

The device or attachment includes a unit which is secured in position with respect to the needle. 45 The unit includes a part or block 14, which is secured to the plate 12 by screws 15 and to the bed 10 by a screw 16. The block 14 has a projection 17 over which the material or cloth M to be stitched and trimmed rides. The block 14 also embodies spaced bearings 18. The unit also includes a trimming or shearing couple consisting of a knife, cutter or trimmer blade 19, and a bar 20 having a shearing or cutting edge 21 with which the blade 19 cooperates. The blade 19 is secured 50 to a shaft 22 for movement therewith. This is

accomplished by the employment of a pivot or arbor 23, fixedly secured to a short arm 24 secured to the shaft 22 by a pin 25. The blade 19 has a hole in one end thereof which receives the reduced adjacent end 26 of the shaft 22, and said blade is also secured to the outer end of the arbor 23, by a screw 27. The shaft 22 is supported by the bearings 18, and has axial and also rocking movement in said bearings. The bar 20 is held in place by the bed 10, plate 12 and block 14, and also by a set screw 28 carried by a lug 29 on the block 14. The block 14 has a groove 30 to receive one edge of the bar 20. By loosening the screw 28, the bar 20 may be slid to various positions of adjustment in order to trim the material or cloth 10 at various distances with respect to the line of stitching indicated at 31. The bar 20 is cut away 15 as at 32 to accommodate a suitable tool for adjusting it. The shearing line of the elements 19 and 20 will be adjacent the edge of the material or cloth being fed in the usual manner, and said line will be parallel to the stitching line 31, as shown most clearly in Fig. 1. Resilient means is employed to yieldingly hold the blade 19 against the cutting edge 21 to thus steady the blade 19 20 and keep it in proper relation with respect to the edge 21. The resilient means consists of a strip 33 of spring steel and this strip 33 is substantially L-shaped and has one end thereof secured to the part 14 by a screw 34, and its opposite end has 25 a notch 35 therein so that said end may be disposed against a shoulder 36 on the projecting end of the shaft 22 opposite that having the blade 19. The shaft 22 is grooved to provide the shoulder 36 and the reduced portion of the shaft is disposed 30 in the notch 35, as shown in Fig. 2. The spring strip 33 constantly urges the shaft 22 axially in one direction to yieldingly hold the blade 19 against the cutting edge 21 of the bar 20. The block 14 has a recess 37 in the under side thereof 35 to accommodate the arbor 23 and the arm 24 and so that the block will serve as a guard therefor. The block embodies a stop 38. When the screw 28 is loosened for the purpose of adjusting the bar 20, the blade 19 may be adjusted at the same time, 40 by reason of the fact that the shaft 22 may have axial movement and also by reason of the resiliency of the spring strip 33. If the blade 19 is removed for any reason, the stop 38 will be encountered by the end of the arbor 23 which projects through the arm 24, and thus prevent displacement of the shaft by the spring strip 33.

The blade 19 is secured to move or rock in a vertical plane with respect to the cutting edge 21, to produce the shearing or trimming action in 55

response to the operation of the arbor 23 as connected with the shaft 22 by the arm 24. This is accomplished by the use of a connecting piece 39, which has a notch 40 to accommodate a portion 5 of the rock 11, the piece 39 being secured to the rock by a suitable fastening element 41. The piece 39 carries a rotatable element 42 having a reduced end 43 constituting an arbor or pivot which is disposed eccentric to the center or axis 10 of the element 42, as shown in Fig. 5. The element 42 is held against rotation by a set screw 44 screwed in a tapped hole in the piece 39. A link 45 has its upper end pivotally and slidably connected with the arbor 23, and the lower end 15 of the link is connected with the pivot 43. It will now be understood that the blade 19 will have rocking motion imparted thereto in response to the rocking motion of the rock 11, through the intervention of the shaft 22, arm 24, arbor 23, link 45, element 42, and piece 39. It is to be understood that the rock 11 will be put in motion 20 when the sewing machine is being operated in the usual manner for stitching the material or cloth. As the material or cloth is being fed in the usual manner to be stitched, an edge portion 25 thereof will be trimmed off in the same operation.

The blade 19 has an upwardly projecting portion 46 which serves as a guard and deflector to cause the cut edges of the material or cloth to move away from the needle so as not to interfere with the proper operation thereof.

When it is desired to adjust the blade 19 for any reason, such as to compensate for a decrease 35 in the size of the blade due to repeated sharpening thereof, the set screw 44 may be loosened and the element 42 rotated to change the position of the pivot 43, to thereby adjust the blade with respect to the cutting edge 21 for the proper cutting or trimming action. Attention is also called to the fact that the sliding connection between the upper end of the link 45 and the arbor 23, enables

adjustments to be made to the cutting bar 20 and the blade 19 without detaching the parts interposing the arbor 23 and the rock 11.

I claim:

1. In an edge trimming attachment for a sewing machine, a shaft mounted for axial and rocking movement, a cutter having one end connected with one end of said shaft, an arm secured to said shaft, an arbor fixed at its opposite ends to the arm and cutter in spaced relation to said shaft, and means so connected with the arbor 10 as to cause motion of the arbor, arm and shaft, to rock said cutter, yet allowing axial movement of the shaft.

2. In an edge trimming attachment, a block 15 embodying bearings, a shaft supported for rocking movement by said bearings, a cutter having one end connected with a projecting end of the shaft, said block having a recess in the underside thereof, an arm secured to said shaft and disposed in said recess, an arbor fixed to the arm and cutter and extending in said recess, and means connected with the arbor to cause motion of the arbor, arm and shaft, to rock said cutter.

3. In an edge trimming attachment for a sewing machine, a fixed part having bearings, a shaft supported by said bearings for axial and rocking movement, an arm secured to said shaft intermediate the ends of the shaft, a bar having a cutting edge on one end thereof, a cutting blade 30 having one end secured to said shaft, an arbor fixed at its opposite ends to said blade and arm to mount the blade for rocking motion with said shaft to produce a shearing action in conjunction with said cutting edge, resilient means secured to said fixed part and engaged with said shaft to urge it axially in one direction to maintain said blade in cooperative shearing relation to said cutting edge, and means connected with the arbor to operate the latter to impart the rock- 25 ing motion to the blade.

JOSEPH CHUDNER.
